UNITED STATES PATENT OFFICE.

JAMES F. THOMAS, OF CLARINDA, IOWA.

TROUSERS-PRESSING DEVICE.

1,258,825.

Specification of Letters Patent. Patented Mar. 12, 1918.

Application filed May 17, 1917. Serial No. 169,272.

To all whom it may concern:

Be it known that I, JAMES F. THOMAS, a citizen of the United States, residing at Clarinda, in the county of Page and State 5 of Iowa, have invented certain new and useful Improvements in Trousers-Pressing Devices; and I do declare the following to be a full, clear, and exact description of the invention, such as will enable others skilled 10 in the art to which it appertains to make and use the same.

My invention relates to that class of devices intended to be clamped upon the creases of trousers to press the same, and 15 the principal object is to provide a foldable device of this class which will thoroughly crease the trousers by strong spring pressure while the garment is clamped therein.

20 In carrying out the above object, a further object is to provide a device which may fold compactly when not in use and which may also fold while the garment is clamped therein, thus permitting the device to be 25 carried in a suit case.

A further object is to provide a novel construction whereby the trousers themselves may act more or less as hinges upon which the device may fold the construction 30 being such that folding of the clamps will not stretch the goods at the folding line.

Yet another object is to provide auxiliary clamps at the ends of the main clamps, adapted to hold the cuffs of the trousers before 35 said main clamps are closed on the creases, thus permitting the garment to be drawn taut to remove all wrinkles.

Another object is to provide an adjustable bar arrangement whereby the trousers 40 are held so stretched as to prevent wrinkling and to remove any wrinkles which may exist when the device is applied to the garment.

A still further object is to construct the 45 clamps with strong pressure so that the trousers may be thoroughly creased without heat, and to provide a simple and efficient means of pressing trousers at any time and in a very simple manner.

50 An additional object is to construct the clamps in a simple and inexpensive, yet in a highly efficient manner, said clamps being so made as to cause them to remain open when applying the device to the trousers.

55 With the foregoing general objects in view, the invention resides in the novel fea-

tures of construction, and unique combinations of parts to be hereinafter fully described and claimed, the descriptive matter being supplemented by the accompanying 60 drawings which form a part of this specification and in which:

Figures 1 and 2 are elevations of the opposite sides of the improved clamp, the latter view showing the device in condition 65 for folding;

Fig. 3 is a vertical section on the plane of the line 3—3 of Fig. 1;

Fig. 4 is a similar view of the device in folded position;

Fig. 5 is a horizontal section on the plane of the line 5—5 of Fig. 1;

Fig. 6 is a detail vertical section on the plane indicated by the line 6—6 of Fig. 1;

Fig. 7 is a detail perspective view showing more particularly one of the auxiliary clamps;

Fig. 8 is a detail end elevation showing a different form of hinge construction.

In the drawings above briefly described, 80 the numerals 1 have reference to a pair of elongated clamps to receive therein the front and rear creases of a pair of trousers, each of said clamps being formed of leaves 2 which are shown constructed of upper and 85 lower sections, although any suitable number of such sections could well be employed. The meeting ends of the leaf sections at one side of each clamp, are connected by a hinge 3, whereas the ends of the sections at 90 the other side of the clamps are free to recede from each other as the device is folded upon the hinges.

It is intended that the hinges 3 shall permit the device to fold compactly whether or 95 not the garment is clamped therein and that one leaf of said hinges shall be adjusted to space the clamp section as in Fig. 2, when the clamps are to be folded, after application to the creases of the trousers. By so 100 adjusting the hinge leaves, the trousers themselves may serve more or less as the hinge upon which the device folds as shown in Fig. 4, a sufficient quantity of material being then provided along the hinge line to 105 prevent stretching of such material as the clamps are folded. Any suitable means could well be employed for adjustably connecting one leaf of the hinges, but a pair of snap fasteners 4 such as those commonly 110 used on gloves and the like, are shown in the drawings for illustrative purposes.

22 For forcing the clamps 1 away from each other after applying them to the creases of a garment, a plurality of transverse bars 5 and 5' are provided. The bars 5 extend 5 straight across the space between the two clamps whereas the others 5' are positioned obliquely to brace the device. The bars 5 are pivoted at one end to the leaf 2 of one of the clamps 1, whereas the other ends 10 thereof are equipped with studs 7 for reception in openings 8 in one leaf of the other clamp. The bars 5', however, are pivoted at 6' to the last named clamp and are formed with studs 7' for reception in openings 8' 15 in the other. This arrangement of bars and adjustable connections at one end thereof, is for illustrative purposes and any suitable construction may be employed.

At the lower ends of the clamps 1, auxiliary clamps 1' are provided, said auxiliary clamps being adapted to grip the cuffs of the trousers before the clamps 1 are closed upon the front and rear creases along the trouser legs. By this means, said legs may 25 be so stretched as to remove all wrinkles therefrom before the clamps are closed.

Although any preferred means could well be employed for connecting the leaves 2 of the clamps 1, the outer edges of said leaves 30 may be stamped so as to form respectively a longitudinal groove 9 and a longitudinal rib 10 in said groove to constitute a hinge upon which the two leaves may rock, C shaped springs 11 being clipped around said outer 35 edges of the leaves as shown most clearly in Fig. 5. The springs 11 not only serve to retain the grooves and ribs in operative relation, but act to close the clamps, which latter are by preference provided on their inner 40 edges with projecting ears 12 whereby they may be easily opened.

Fig. 8 discloses the grooved and ribbed portions 9' and 10' respectively of the leaves 2', so constructed as to overcome the tension 45 of the springs 11' when the clamp is opened, thus causing said clamp to remain in open position until closed by hand. It is the frictional engagement of such portions, caused by the resiliency thereof, that causes the 50 clamps to remain open.

In most cases, strips of felt or the like 13 will be cemented or otherwise secured to the inner faces of the several leaves 2, in order that they may effectively grip the garment.

55 In use, the two clamps are separated by disengaging the studs 7 and 7', said clamps being then separately applied to the front and rear creases of the trousers, taking care that the clamps 1' be first applied so that the 60 garment may be stretched before the clamps

1 are closed. After applying the clamps in this manner, the studs 7 and 7' are engaged with their openings 8 and 8' to hold the two clamps spaced apart sufficiently to prevent wrinkling of the garment. An eye 14 may 65 be provided for supporting the device in an extended position, but by folding the two clamps upon the hinges 3, the entire pressing device may be readily carried in a suitcase while the trousers are gripped in said clamps. When this folding is done with the trousers in the device, it is necessary to first release the fasteners 4 so that the hinges 3 may be adjusted to space the two sections of 70 said clamps so as to prevent stretching the 75 trousers legs on the folding lines. Were it not for some such adjustable connection between the sections of the clamps, the folding thereof would stretch and injure the garment. 80

I claim:

1. A trousers pressing device comprising a pair of elongated clamps to receive the creases of the garment, each clamp consisting of a pair of leaves to grip the creases therebetween, each leaf being formed of a plurality of sections disposed end to end, hinges connecting the sections at one side of each clamp, each hinge being adjustably connected with one of said sections, to permit said sections to be moved away from each other before folding, whereby to prevent stretching of the trousers when folding. 85

3. A trousers pressing device consisting of a pair of metal strips, one having a longitudinal groove stamped in one edge and the other having stamped on its corresponding edge a longitudinal rib received in said groove, and C-shaped clamps clipped around 90 said edges of the strips. 95

3. A trousers pressing device comprising a pair of clamps to receive the creases of the garment, each clamp consisting of a pair of leaves whose outer edges are stamped to form interengaging ribs and grooves, and 105 C-shaped springs clipped around said edges to clamp the leaves together, one leaf of each clamp being slit transversely throughout its width above its lowermost spring, whereby to provide a pair of auxiliary clamps to grip 110 the cuffs of the trousers when applying the device.

In testimony whereof I have hereunto set my hand in the presence of two subscribing witnesses.

JAMES F. THOMAS.
